(57) **CLAIM**

The ornamental design for a toy remote controller, as shown and described.

DESCRIPTION

FIG. 1 is a perspective view of the top, rear and right side of a toy remote controller according to our new design;

FIG. 2 is a top plan view thereof;

FIG. 3 is a bottom plan view thereof;

FIG. 4 is a front elevation view thereof;

FIG. 5 is a rear elevation view thereof; and,

FIG. 6 is an elevation view of a left side thereof, the right side being a mirror image thereof.
